Lewis Keachler,
INVENTOR

BY Victor J. Evans

ATTORNEY

John B. Jr.,
WITNESS:

Patented Sept. 5, 1922.

UNITED STATES PATENT OFFICE.

LEWIS KEACHLER, OF PHILADELPHIA, PENNSYLVANIA, ASSIGNOR OF ONE-HALF
TO NORA C. STRAYER, OF PHILADELPHIA, PENNSYLVANIA.

FURNITURE FIXTURE.

Application filed December 17, 1921. Serial No. 523,108.

To all whom it may concern:

Be it known that I, LEWIS KEACHLER, a citizen of the United States, residing at Philadelphia, in the county of Philadelphia and State of Pennsylvania, have invented new and useful Improvements in Furniture Fixtures, of which the following is a specification.

This invention relates to furniture fixtures and it has more particular reference to a novel form of fixture for connecting together the rocker rail and legs of a rocking chair, the primary object being to provide a fixture of the character referred to which may be readily adapted for use when repairing a break between the legs and the rocker rail and by the use of which said parts may be reconnected in secure relation to each other.

Another object of this invention is to provide a fixture of the type referred to which consists of an inverted U-shaped member provided with an integral enlargement having a threaded socket portion for the reception of the lower correspondingly threaded end of the chair leg, the rocker rail being adapted to seat snugly in the inverted U-shaped member and be securely held therein, the unique manner of holding said rocker rail in the inverted U-shaped member comprising means whereby the strain between said fixture and the rocker rail when the chair is in use is directed to the upper curved edge of the rocker rail and that portion of the fixture contacting therewith.

With the foregoing and other objects in view as will be more clearly apparent from the following description my invention consists essentially in the novel features of construction, combinations and arrangements of parts hereinafter fully described and more specifically defined by the appended claim.

In the further disclosure of the invention reference is to be had to the accompanying sheet of drawings constituting a part of this specification and in which like characters of reference designate the same or corresponding parts in all the views.

Figure 1 is a fragmentary side elevation of portion of the rocker and an associated leg said parts being connected together by my improved furniture fixture.

Figure 2 is a side elevation of my improved furniture fixture by itself; and,

Figure 3 is a transverse section of the

Referring more particularly to the views it will be seen that my invention resides essentially in providing a fixture of a character adapted for connecting a leg and rocker rail of a rocking chair together but primarily the purpose of this invention is to furnish a means for repairing a break or disconnection between a leg and the rocker rail, that is to repair the breaking of the leg or tenon adjacent its point of connection with the rocker rail.

In the drawings the numeral 4 designates a fragmentary portion of a rocking chair rocker rail and 5 indicates the lower end of a leg adapted to be secured to and supported by said rocker rail 4. Ordinarily in the manufacture of rocking chairs the legs are tenoned into the rocker rail and it is at this point of juncture between the leg and rocker rail that a break invariably takes place due to undue strains or weakness in the materials from which said parts are manufactured. To overcome this weakness and mainly provide a means for repairing a fracture or breakage between the leg 5 and the rocker rail 4 I employ my novel connecting fixture 6 which consists of an inverted U-shaped member 7 having an integrally formed threaded socket portion 8 superposed thereon.

The inverted U-shaped member 7 of the fixture 6 is formed with depending side portions 9 spaced apart and integral with the bridge portion 10, said depending side members 9 having opposed openings or holes 11 therein for a purpose to be later on explained. The opposed inner faces of the depending side members 9 are substantially parallel, whilst the underface of the bridge portion 10 of the inverted U-shaped member is of a curvature substantially conforming to the curvature of the upper edge of the aforesaid rocker rail 4.

The hereinbefore mentioned socket portion 8 is integral with the bridge portion 10 of the fixture and it is provided with a vertical threaded aperture 12 therein. In repairing or connecting together the leg 5 to the rocker rail 4 the lower portion of said leg 5 is threaded as at 13—Figure 1—to engage in the threaded socket 12 and thereby securely hold said leg in place. The invert-

ed U-shaped portion of the connection fixture 6 is next positioned over the rocker rail 4 with the curved face of the bridge portion 10 firmly seating on the upper edge of said rocker rail whilst the side members 9 thereof embrace and snugly engage the side walls of said rocker rail thereby preventing any transverse movement of the rail with respect to the fixture. In order to securely hold the rail 4 with respect to the connecting fixture 6 I preferably employ a stud 14 having a screw-threaded portion 15 intermediate its ends, said screw-threaded portion being firmly screwed into the rocker rail whilst the plain portions at the ends of said studs 14 are snugly journaled in the hereinbefore mentioned holes or apertures 11. Thus it will be seen that the ends of the stud 15 being journaled as described constitute end 20 bearings that support the rocker rail 5 in fixed relation relative to the connecting fixture 6. Furthermore it will be readily seen that with a connecting fixture of the character described that the strain between the fixture 6 and the rail 4 is directed to the upper face of the rocker rail 4 and the bridge portion 10 of said connecting fixture, whilst the journaling of the free ends of the stud 15 in the depending side members 9 of the inverted U-shaped portion 7 will relieve the side members 9 from any strain.

Whilst there has been shown and described a preferred embodiment of my invention it will be apparent that the same is susceptible of slight changes and variations

to accommodate it to different sizes and patterns of rocking chairs and the right is hereby reserved to make such changes or variations that fairly lie within the scope of the appended claim.

Having described my invention, what I claim as new and desire to secure by Letters Patent is:

A furniture fixture of the character described for connecting a leg to the rocker rail of a rocking chair, said rocker rail having a transversely threaded hole therein, said fixture comprising an inverted U-shaped member having an integrally formed threaded socket adapted to receive the correspondingly threaded end of the aforesaid leg, said inverted U-shaped member being formed with spaced depending side members integral with a bridge portion and said bridge portion having a longitudinal curvature on its underface conforming to the curvature of the rocker rail, opposed apertures in the side members adapted to register with the threaded opening in the rocker rail, and a stud having a threaded portion intermediate its ends for insertion in the aforesaid threaded opening whilst the ends of said stud are adapted to be journaled in the apertures in the side portions of the inverted U-shaped member, and the curved inner face of the bridge portion thereof being adapted to seat on the upper curved face of the rocker rail.

In testimony whereof I affix my signature.

LEWIS KEACHLER.
